UNITED STATES PATENT OFFICE.

MICHAEL BENEDICT, OF NEW YORK, N. Y.

DESIGN FOR A CASE FOR COIN-CONTROLLED MECHANISM.

SPECIFICATION forming part of Design No. 36,087, dated September 30, 1902.

Application filed March 5, 1902. Serial No. 96,854. Term of patent 3½ years.

To all whom it may concern:

Be it known that I, MICHAEL BENEDICT, a citizen of the United States, residing at New York, in the county of New York and State of New York, have invented and produced a new, original, and ornamental Design for a Case for a Coin-Controlled Mechanism, of which the following is a full, clear, and exact description, reference being had to the accompanying drawings, and the numerals of reference marked thereon, which form a part of this specification.

This invention relates to a new and original design for a case employed in connection with a coin-controlled mechanism for testing the force of air which is to be blown from the lungs of a person; and the invention consists in the peculiar shape and ornamentation of the case or box and in the various ornamental features of the same, all of which will be hereinafter more particularly set forth and claimed and which will be fully understood by reference to the accompanying drawings, in which is illustrated an embodiment of the invention.

In the said drawings, Figure 1 is a front elevation of a case or box embodying the leading features of the design, and Fig. 2 is a side elevation of the same.

As shown in the said drawings, the leading or material feature of my design consists in the general appearance of a case or box 1, (clearly represented in Fig. 1 of the drawings,) the same comprising an ornamental front or face 2, provided with a glass front or window 3, through which are exposed to view other ornamental features, all of which are a part of the design. The said front comprises an

ornamental base 4, a pair of ornamental corner posts or pillars 5, and an ornamental top 6. Between the said posts 5 and resting upon the base 4 is an ornamental panel 7 and upon which is supported the said glass panel or window 3. Between the upper end portions of said posts 5 and between the upper edge of the said glass panel or window 3 and the lower front edge of the top 6 is another ornamental panel 8. The sides 9, as well as a pair of rear corner-posts 10, as will be seen from an inspection of Fig. 2 of the drawings, are of plain ornamentation. The interior ornamentation of the said case or box 1, which is exposed to view through the glass panel or window 3, consists of a concave wall or partition 12, an arc-shaped indicator-card 13, which extends rearwardly, but in an upwardly-inclining direction toward radially-arranged supporting-blocks 14. Upon these blocks are a series of semicircularly-disposed burners 15, made in imitation of candles, all arranged with a view of producing a highly ornamental and esthetic appearance.

Having thus described my invention, what I claim as new, and desire to secure by Letters Patent, is—

The ornamental design for a case for a coin-controlled mechanism as herein shown and described.

In testimony that I claim the invention set forth above I have hereunto set my hand this 4th day of March, 1902.

MICHAEL BENEDICT.
